UNITED STATES PATENT OFFICE.

EMANUEL O. GOLDSMITH, OF MEMPHIS, TENNESSEE.

FLOOR LAMP.

Application filed October 8, 1921. Serial No. 503,480.

To all whom it may concern:

Be it known that I, EMANUEL O. GOLDSMITH, a citizen of the United States, residing at Memphis, in the county of Shelby 5 and State of Tennessee, have invented certain new and useful Improvements in Floor Lamps; and I do hereby declare the following to be a full, clear, and exact description of the invention, such as will enable others 10 skilled in the art to which it appertains to make and use the same.

The present invention relates to improvements in floor lamps and has for an object to provide a floor lamp structure which is 15 modified and arranged to receive a table, an illuminated clock structure, costumer hooks and a magazine holder to thereby provide in a single article of furniture a unitary device adapted to fulfill these various 20 functions.

Another object of the invention is to provide an article of furniture in which the parts will be collapsible against a single post so that when not in use the device may 25 assume the usual appearance of a floor lamp.

A further object of the invention resides in providing a device of the above character in which a simple, inexpensive and compact construction is had and which will 30 occupy but a small space and yet serve all the functions of a great number of articles of furniture which now require considerable house space.

With the foregoing and other objects in 35 view, the invention will be more fully described hereinafter, and will be more particularly pointed out in the claims appended hereto.

In the drawings, wherein like symbols 40 refer to like or corresponding parts throughout the several views,

Fig. 1 is a view in elevation of an improved article of furniture constructed according to the present invention.

Fig. 2 is a vertical sectional view on an enlarged scale, with parts broken away.

Referring more particularly to the drawings, 1 designates a post or standard which is erected upon a base 2 having castor domes 45 or suitable feet 3 to support it at an elevation above the floor and to give the device an ornamental character. The base 2 is wide as compared with the column 1 and hence affords a shoulder extending about the column which rises centrally from such base. I avail myself of the space and support

afforded by this shoulder to place thereon a holder for magazines or the like articles. This holder consists of a V-shaped trough, as this type of trough is particularly desirable both from an ornamental and useful viewpoint. The angled bottom of the trough coincides substantially with the outer edge portion of the shoulder, and an inwardly directed flange 5 extends from the angle to lie 50 inwardly over a considerable area of the shoulder and to thus find an extensive support for the holder 4. This allows the outer portion of the holder to extend beyond the shoulder and to form with the base 2 a 55 pleasing and ornamental appearance, at the same time providing a holder of larger capacity than could be provided in the confines of the shoulder itself. The upper inner edge of the holder is provided with a downwardly directed flange 6 for fitting against the post 1.

Above the magazine holder, a table is provided composed of the leaves 7 in any suitable number arranged as indicated at 8 in 60 the upper ends of recesses 9 made in the post for the table leaves to collapse downwardly into. The table leaves are provided with braces 10 pivoted as indicated in 11 to brackets 12 held under the outer portions of the 65 leaves. The braces 10 are jointed intermediate as indicated at 13 to permit of folding against the bottoms of the leaves just prior to the collapse of the leaves into the recesses 9. Holders 14 for cards or other articles 70 may be carried beneath the table leaves as shown.

Other recesses 15 are formed in the post 75 above the table to receive the arms 16 which are hinged to the post as at 17 and have foldable braces 18 for supporting such arms in a horizontal extended position and up beneath the shoulder formed by the enlargement 19 of the post. This enlargement is made hollow as indicated in Fig. 2 100 to receive the mechanism of a clock 20 adapted to be illuminated by lamps 21 carried upon pivoted uprights carried upon the outer ends of the arms and held in operative position by foldable braces 23 secured between the upper portions of the uprights and the arms 16 and permitting of the uprights being folded down upon the upper sides of the arms when the latter are to be collapsed into the recesses 15. The enlargement 19 105 thus serves a dual function of housing the clock mechanism and also creating a

shoulder with the post against which the arms 16 may abut and be held rigidly in an upper position.

The costumer hooks 24 are located above the clock mechanism and are preferably held as by the jointed braces 25 in an inclined position as shown in both figures. The hooks 24 are hinged as indicated at 26 to the post and in the upper ends of the recesses 27 into which the hooks may fold when out of use. The hooks 24 may be of the character shown or any other suitable form.

Upon the upper end of the post 1 is carried a lamp socket 28, preferably a clustered socket adapted to receive a number of lamps. The lamps will have suitable wiring connections with a wall or floor plug. Arms 29 are made fast to the post just beneath its upper end and extend outwardly to receive the lamp shade 30.

In use, the costumer hooks 24, arms 16 and table leaves 7 may be folded in their respective recesses and the device then assumes the customary appearance of a floor lamp. However, when it is desired to use the device as a hat and coat rack, the hooks may be pulled outwardly and caused to resume the position shown. The table may in like manner be brought into operating position for playing cards or for other purposes.

The arms 16 are also lifted to illuminate the clock structure and to give ornamental appearance to the device, as also to provide a more effective light for reading and for use in connection with the table. It will be appreciated from the foregoing that I have

provided an extremely attractive article of furniture which combines a number of devices and which may be contained in a compact space.

40

What is claimed is:

1. A floor lamp and the like comprising a column, means for supporting the same, a lamp structure carried by the column, said column having an enlargement intermediate its height forming a shoulder with the portion of the column therebeneath, a clock mechanism mounted in said enlargement, arms pivoted to the column beneath the enlargement and adapted to encounter the enlargement when raised to an upper position, said arms adapted to be collapsed against the column, means for supporting said arms also adapted for collapse, and collapsibly mounted illuminating means for the clock mechanism on the arms, substantially as described.

50

2. A floor lamp and the like comprising a column, a base supporting the column, a magazine holder carried by the base about the column, a table having collapsible leaves secured to the column above the base, a clock structure mounted on the column above the table, arms pivoted to the column below the clock structure and having collapsible braces for supporting the same, collapsible illuminating means carried by the arms, collapsibly mounted costumer hooks on the column above the clock mechanism, and a lamp structure at the top portion of the column, substantially as described.
